Fred Wacker.

Patented May 22, 1923.

Des. 62,406

UNITED STATES PATENT OFFICE.

HERBERT NALTY, OF LONDON, ENGLAND.

DESIGN FOR A JEWELRY TRINKET.

Application filed September 13, 1922. Serial No. 3,711. Term of patent 3½ years.

To all whom it may concern:

Be it known that I, HERBERT NALTY, a subject of the King of Great Britain and Ireland, resident of 57 Great Marlborough Street, Regent Street, London, W. 1, England, have invented a new, original, and ornamental Design for a Jewelry Trinket, of which the following is a specification, reference being had to the accompanying drawing, forming part thereof.

The figure is a perspective view of a jewelry trinket showing my new design.

I claim:

The ornamental design for a jewelry trinket as shown.

HERBERT NALTY.

Witnesses:

H. L. SHARP,
M. E. NALTY.
